UNITED STATES PATENT OFFICE.

JULIAN T. MAYER, OF NEW YORK, N. Y., ASSIGNOR TO J. & C. FISCHER, OF NEW YORK, N. Y.,
A CORPORATION OF NEW YORK.

OPERATING CONNECTION FOR PEDAL-HIDING PANELS.

No. 890,678.

Specification of Letters Patent.

Patented June 16, 1908.

Application filed October 15, 1907. Serial No. 397,538.

To all whom it may concern:

Be it known that I, JULIAN T. MAYER, a citizen of the United States, residing at New York, in the county of New York and State 5 of New York, have invented new and useful Operating Connections for Pedal - Hiding Panels, of which the following is a specification.

This invention relates to mechanism for 10 operating a pedal hiding panel on a musical instrument.

It is especially designed for the so-called combination pianos but it may be applied to 15 separate players and other instruments of similar character.

The principal objects of the invention are 20 to provide means whereby the panel when it swings open will be cushioned in a simple and effective way by an instrumentality which 25 will not be subject to any appreciable amount of wear, as in its preferred form it has no parts which work against each other with friction; also to provide for transmitting motion between the panel and such instrumentality in a proper ratio, for restoring the same; to automatically latch the panel in 30 closed position and hold it there, and to keep the latching means in proper place so that the panel will engage it in such a way as to 35 secure the locking action; to locate the parts in such position that they can readily be manipulated by the player; to provide the panel with means whereby the same may be closed by action of the foot of the operator, and especially to provide means whereby 40 when the latch is released, the panel will be forced to swing outwardly from its closed position; and generally to improve and simplify the construction of a panel operating mechanism of this character.

Reference is to be had to the accompanying drawing which shows a preferred embodiment of the invention and in which

Figure 1 is a transverse vertical sectional view of the same, Fig. 2 is a front elevation showing the panel in closed position, Fig. 3 is an enlarged sectional view of a detail, and Fig. 4 is a plan of the drum.

The drawing illustrates the invention as 50 applied to a piano case 10 having an overhanging front portion 11, as is usual. This case has a panel opening 12 which is designed to be closed by a panel 13 which is hinged or pivoted to the casing by means of hinges or 55 the like 14.

In the form illustrated, the hinges are at the bottom of the panel and the same swings outwardly about them to open position. In this form also the pedals 15 are shown as pivotally mounted on the inside of the panel 60 itself and are provided with folding connections 16 of any of the ordinary kinds which are well-known in this art, so that when the panel swings upwardly to closed position, the connections 16 will fold up in a well known 65 way within the casing.

The panel is provided with one or two depressions or notches 20 in its outer edge in which the toe of the operator may be inserted to raise the panel and throw it up into 70 closed position. It is designed that when this is done, the panel shall be automatically locked in closed position, and for this purpose it is provided with a plate 21 having a slanting surface 22 and a notch 23 located on its 75 upper edge. On the inside of the casing above the opening 12 is located a plate 24 on which is pivotally mounted a latch 25 designed to be operated by a spring 26. This spring engages a projection 27 on the latch 80 and the latch will operate automatically when the panel is closed to lock the same.

In order to operate the latch when it is desired to open the panel, a lever 28 is employed engaging the projection 27. This lever is operated by a rod 29 which has a handle 30 thereon. This rod extends through the top of the lower part of the casing and is located under the overhanging part 11 so that the handle is at the front of the same and is 96 within easy reach of the operator.

It will be observed that in this construction, the latch 25 would fall down when the panel was open if it were not for the fact that the portion 31 of the casing is located in such 95 position as to limit the motion of the lever 28 so as to hold the latch up in all positions thereof.

In order to provide for opening the panel automatically when the latch is released, 100 therefrom, means is located within the casing for constantly bearing with a resilient force on the rear of the panel when the same is closed so that when the latch is withdrawn, the panel will be forced outwardly sufficiently 105 far to enable it to be opened the rest of the way by gravity. This means is shown in the present instance as in the form of a pair of springs 35 each having one end fixed inside the casing and the other end in position to 110

2
bear on the rear of the panel when closed. It will be seen that these springs act also to cushion the force of the closing movement of the panel when the same is swung upwardly with a quick motion. On opening the panel in the manner set forth above, it will be obvious that after it begins to fall by gravity, its motion will be accelerated so that ordinarily it would drop to the floor with a heavy blow on its rubber cushions 36. In order to avoid this, mechanism is provided whereby the falling motion of the panel is checked toward the end of the same. This preferably is in the form of a pneumatic of well known construction connected with the panel. In the present instance this is shown as of the following construction.

Connected with the panel is a flexible connection 37 which is wound on a drum 38. This drum preferably is constructed in two parts which I term spools 39 and 40 and which rotate together. The former of these has a smaller diameter than the latter. The larger spool is adapted to receive a flexible connection 37 while the smaller receives a second flexible connection, or the other end 41 of the connection 37, which is connected with the movable leaf 42 of a pneumatic 43. For convenience I shall refer to the two ends 40 of this cable as two flexible connections, as they operate substantially in the same way in either case. I prefer, however, to use one continuous cable, starting around the large spool, wound around several times preferably 45 and veering off through a slot 50 in the rim of the large spool down on the smaller spool. This pneumatic as shown is of an ordinary type. It preferably is provided with a spring 44 for restoring it to normal position and is located on a stationary shelf or bracket 45 within the casing. The operation of this part of the device is very simple. When the panel falls outwardly, the cable or other flexible connection 37 is unwound from the spool 40 and the cable 41 (being wound on its spool in the opposite direction) will be wound up taking the movable leaf 42 with it. It will be seen that the power is multiplied here, although that is not absolutely necessary, but 50 the pneumatic is opened against the atmospheric pressure. As it is provided with a small air inlet opening 47 varying in size according to the weight of the parts to be lifted, the speed with which it can open is small 55 compared with the natural falling velocity of the panel. Consequently the latter is checked in such a way that it drops to the floor gradually.

During all the time that the panel is open, the spring 44 continues to exert a pressure on the movable leaf 42 to close it and consequently this spring will exert some force to assist in closing the panel, it being understood that on the closing motion, the pneumatic will have no effect as it is not posi-

tively caused to move by the panel on its return. In fact, if desired, the spring may be made strong enough to have a material influence on the closing of the panel. As soon as the panel commences to close, the spring 70 commences to operate to restore the pneumatic to normal position and as the pneumatic has a large air outlet opening 46 controlled by a valve under the influence of a light spring 48, it closes as rapidly as the 75 panel and pedals rise, the spring 44 thus assisting in lifting the panel and pedals. It is at this time that the spring 35 acts to cushion the closing force of the panel.

It will be seen that the checking of the 80 downward motion of the panel is thus secured in a very simple manner by mechanism which has no parts which move against each other to produce friction and wear and which although efficiently checking the device, will 85 have no force to tend to prevent the opposite motion of the panel but on the contrary will have some force to assist in moving it in the other direction. In addition to this, the invention provides for automatically opening 90 the panel in a simple and efficient way and for automatically locking it.

While I have illustrated and described a preferred embodiment of the invention, I am aware that many modifications may be made 95 thereby by any person skilled in the art without departing from the scope of the invention as expressed in the claims. Therefore, I do not wish to be limited to the particular details of construction shown and 100 described, but

What I do claim is:—

1. In a musical instrument, the combination of a movable panel, a drum having spools of different diameters, a flexible connection wound on the larger spool and connected with the panel and wound on the smaller spool, and means connected with the part of said connection wound on the smaller spool for checking the opening motion of said 110 panel.

2. In a musical instrument, the combination of a panel for hiding the pedals mounted to swing outwardly about a pivot, a drum, a flexible connection adapted to be wound 115 on the drum and connected with the panel, and a pneumatic connected with the drum for checking the opening motion of said panel.

3. In a musical instrument, the combination of a movable-panel, a drum having spools of different diameters, a flexible connection adapted to be wound on the larger spool and connected with the panel and to be wound on the smaller spool, and a pneumatic 120 connected with the connection.

4. In a musical instrument, the combination of a movable panel, a drum having spools of different diameters, a flexible connection adapted to be wound on the larger 125

spool and connected with the panel, and adapted to be wound on the smaller spool, a pneumatic connected with the flexible connection, and a spring bearing on the pneumatic for restoring the same to normal position when the panel is closed.

5. In a musical instrument, the combination of a vertical movable panel, means connected therewith for cushioning the opening motion thereof, yielding means inside the instrument engaging the rear of the free end of the panel when closed for pushing the panel open, and means for holding the panel in closed position, whereby when the holding 10 means is released, the said yielding means will cause the panel to fly open.

6. In a musical instrument, the combination of an outwardly movable panel, a pneumatic, a connection from the panel to the 20 pneumatic for operating the pneumatic against the atmospheric pressure when the panel moves outwardly, a spring for restoring the pneumatic when the panel is closed and for assisting in closing the panel, and a 25 second spring for engaging the panel when closed and tending to push the panel open.

7. In a musical instrument, the combination of an outwardly movable panel, a pneumatic, means for operating the pneumatic 30 against atmospheric pressure when the panel moves outwardly to check the outward motion thereof, a spring for restoring said pneumatic to normal position when the panel is closed and for assisting in closing the panel,

and a second spring for cushioning the closing motion of the panel.

8. The combination with a musical instrument casing having an overhanging front portion, of a swinging panel in the lower portion thereof, a spring for engaging said panel 40 when closed and normally tending to push the panel open, a spring latch for engaging the panel when closed and automatically locking the same in closed position, a lever for operating said latch to release the same, 45 and a rod connected to said lever for operating it and located on the lower side of said overhanging portion and extending substantially to the front thereof.

9. In a musical instrument, the combination of a swinging panel having a notch in one edge thereof, a pivoted spring latch adapted to engage in the notch and lock the panel in closed position, a lever for operating said latch, and means for operating the lever, 50 said casing extending into such position as to hold the lever against the latch to hold the latch in position to be engaged by the panel when closed, whereby the latch will be in position to lock the panel automatically. 55

In testimony whereof I have hereunto set my hand, in the presence of two subscribing witnesses.

JULIAN T. MAYER.
